[57] **CLAIM**

The ornamental design for a wall storage panel for entertainment media, as shown and described.

DESCRIPTION

FIG. 1 is a top, front, and right side perspective view of a wall storage panel for entertainment media showing my new design, the left side being a mirror image of that shown;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a front elevational view of a second embodiment thereof, the only difference from the first embodiment residing in the configuration of elements on the front elevation and in the vertical dimension.

FIG. 1

FIG. 2

FIG. 6

FIG. 3

FIG. 4

FIG. 5
